COLLAPSIBLE CORE.

1,241,942.

Specification of Letters Patent. Patented Oct. 2, 1917.

Application filed July 3, 1916. Serial No. 107,301.

To all whom it may concern:

Be it known that I, WILLIAM Y. DUNCAN, JR., a citizen of the United States of America, residing at Springfield, in the 5 county of Hampden and State of Massachusetts, have invented certain new and useful Improvements in Collapsible Cores, of which the following is a specification.

This invention relates to collapsible cores 10 and particularly to improved cores of this type which are adapted for use in the manufacture of the outer casings or shoes of pneumatic tires.

An object of the invention is to provide a 15 collapsible core consisting of an annular ring formed with a plurality of sections and slideable devices in certain of the sections adapted to overlap the joints between sections to securely hold the latter in ring 20 forming position.

Another object of the invention is to provide in a collapsible core having a plurality of sections adapted to abut with one another to form an annular ring, means coöperating 25 with the abutting end faces of the sections to prevent relative lateral displacement thereof and curved slideable keys movable in a circular slot formed in the core ring to overlap the joints between abutting sections 30 to prevent inward displacement thereof, said keys being movable to a position wherein the sections may be withdrawn inwardly when desired.

Other objects and advantages will appear 35 in the description to follow and in the annexed claims.

For the purpose of illustrating one way in which the invention may be practised, a preferred embodiment thereof is shown in 40 the accompanying drawings, in which—

Figure 1 is a plan view, partly in section, of the assembled core;

Fig. 2 is a side elevational view thereof;

Figs. 3 and 4 are fragmentary views showing modifications of the structure shown in 45 Fig. 2;

Fig. 5 is a cross sectional view taken on the line 5—5 of Fig. 1 and looking in the direction of the arrows; and

50 Figs. 6, 7, 8, and 9 are diagrammatical views showing modifications in the shape of the sliding key shown in Fig. 5.

Referring to these drawings in detail, the assembled core is an annulus and is made up 55 of a plurality of sections 1 in the customary

way to permit removal of the core from the tire shoe after the curing operation. The number of sections into which the core is divided may be varied as desired but, in practice, the division of the core, as shown 60 in Fig. 1, into four sections, two of which are relatively small, has been found satisfactory. In the drawing, the end faces of the smaller sections 1 have been shown as diverging inwardly toward the center of the 65 core ring to permit ready withdrawal, but they may, if desired, be substantially parallel or may diverge at other angles than that shown, as it is only essential that the several sections be arranged for inward withdrawal from the tire shoe. 70

The sections 1 have the cross sectional shape shown in Fig. 5, and the contour of the outer portions thereof may be varied to suit the desired conformation of the inner 75 surface of the tire shoe. The usual cored passages 2 are provided in the outer portions of the sections, as shown in Figs. 1 and 5 and extending inwardly from the outer portions are centrally arranged webs 80 3, at the bases of which and extending on either side thereof, are flanged portions 4. Within each inner flange 4 and in concentric relation therewith is formed an arcuate slot 5, which is inclosed on three sides and 85 partially inclosed on the fourth and inner side except for a narrow slot 6 leading from slot 5 to the inner face of the flange. The ends of the several slots 5 and 6 coincide to form true circular slots, and curved keys 90 7, of any suitable number depending on the number of core sections 1, are arranged to slide in slots 5, the keys being provided with pins 8 which ride in slots 5 and protrude beyond the inner faces of flanges 4 for convenient actuation of the keys. The latter may 95 be of square cross section as shown in Fig. 5, or of any other suitable or desirable shape, such, for example, as the "dovetail" keys 9 and 10, shown in Figs. 6 and 7, respectively, or the round and half-round keys 11 and 12, shown in Figs. 8 and 9, respectively. Preferably the corners of keys 7 are rounded, as shown in Fig. 5, and several holes 13 are drilled laterally in flanges 4 to permit oil 105 or other lubricating material to be introduced into slot 5 when desired. The number and length of keys 7 will depend upon the particular subdivision of the core which is adopted, but, with the arrangement of 110

core sections shown in Fig. 1, it has been found that two keys, each of such a length as to cover substantially a ninety degree arc of slot 5, is a satisfactory arrangement.

- 5 The several sections 1 are adapted to abut with one another on the lines 14 to form a complete annular core ring and 15 represents merely the usual filler plates which may be considered as fastened to and constituting a part of the smaller core sections. At each joint between the sections, keys 16 are provided which may be fixed in one of the abutting sections (preferably the larger sections) by any suitable means, such as a 15 driving fit, for example. These keys 16 may be round, as shown in Fig. 2, square or half round in cross sectional shape, as shown at 17 and 18 in Figs. 3 and 4, respectively, or of any other suitable or desirable shape. 20 With the parts positioned as in Fig. 1, the core may be taken apart by first moving the keys 7, so that each lies entirely within the slot 5 in one of the larger core sections, and then withdrawing the smaller 25 sections 1 inwardly from the tire shoe, leaving keys 16 fixed in the two larger sections. The two larger sections may then be readily removed from the tire shoe. In assembling the core, the sections 1 are fitted together in 30 abutting relation, and the keys 16 serve to position the sections laterally, as well as circumferentially so that the core may be assembled to form a true annular ring. It is then necessary to hold the several sections 35 together, and this is accomplished by sliding keys 7 from the slots in the larger core sections to the positions shown in Fig. 1, wherein each key 7 passes completely through the smaller core sections, projects 40 a substantial distance into each of the abutting sections and overlaps the joints therebetween.

Thus, the sections may be securely locked together quickly and conveniently by simple 45 means as distinguished from the bolt connections, locking and binding rings heretofore used which not only require the use of tools (frequently of special character) but consume valuable time for their operation. 50 The present structure is characterized by an entire absence of bolts and other special devices customarily employed, and the core is arranged to be assembled and taken apart rapidly and conveniently without the aid of 55 tools.

The invention has been defined in a preferred form with detailed variations for 60 illustrative purposes, but the scope of the invention is defined by the appended claims rather than by the foregoing description.

What I claim is—

1. A collapsible core, comprising, an an-

nular ring made up of a plurality of sections and slideable devices adapted to lie wholly within certain of said sections and adapted 65 to be moved partially within abutting sections to overlap the joints therebetween, whereby the sections are held in coöperative relation to one another.

2. A collapsible core, comprising, a plurality of sections adapted to abut with one another to form an annular ring, and slideable devices, each arranged to lie partially within adjacent sections to overlap the joint therebetween, whereby the sections may be 75 locked together, each of said devices adapted to be moved to lie wholly within a section so that the sections may be separated one from another, as desired.

3. A collapsible core, comprising, an annular ring made up of a plurality of sections, said sections having interlocking end connections to prevent relative lateral displacement and slideable devices arranged to lie wholly within certain sections and adapted 85 to be moved partially within abutting sections to overlap the joints therebetween.

4. A collapsible core, comprising, an annular ring made up of a plurality of sections, a circular slot formed in the ring adjacent the 90 inner edge thereof, keys curved to fit said slot and arranged to be moved from positions wholly within certain sections to positions wherein the joints between abutting sections are overlapped, and keys in the end 95 faces of certain sections adapted to interlock with abutting sections to prevent relative lateral displacement.

4. A collapsible core, comprising, an annular ring made up of a plurality of sections 100 which are so formed that at least one thereof is bodily removable inwardly, keys at the joints between the sections arranged to prevent relative lateral displacement of the sections, slots formed in each of the latter 105 and arranged to coincide with one another to form a circular slot and keys movable in said slots to overlap abutting sections, and prevent inward displacement thereof.

6. A collapsible core, comprising, an annular ring made up of four sections, two of which are relatively small and arranged for bodily removal inwardly, slots formed in each section and arranged to coincide to form a circular slot and curved keys slideable 115 in said slots and adapted to lie wholly within the slots in the larger sections, said keys adapted to be moved to a position wherein they extend entirely through the smaller sections and project therebeyond on either side 120 to overlap the joints between the smaller and the adjacent larger sections.

WILLIAM Y. DUNCAN, JR.
